FUEL BURNER CONTROL SYSTEM

Siegfried G. Isserstedt, Minneapolis, Minn., assignor to Minneapolis-Honeywell Regulator Company, Minneapolis, Minn., a corporation of Delaware

Application November 17, 1941, Serial No. 419,465

9 Claims. (Cl. 158—28)

The present invention relates generally to a control system for fluid fuel burners, and is directed more particularly to a system employing automatic starting and stopping means in which the burner will be shut down immediately upon a flame failure at the burner and yet will interpose a substantial standby or scavenger period, before the burner can be automatically started again.

In prior art devices it has been customary to supply combustion responsive devices which take a substantial amount of time, upon the extinguishment of the flame at the burner, to move from their hot to their cold positions. In such instances it is customary to run the starting circuit through the cold contact of the combustion switch so that following a flame failure the burner cannot be restarted until the combustion responsive device closes its cold contact. Such a system is satisfactory where the combustion responsive device moves slowly enough to provide a substantial delay before closing its cold contact.

It is the purpose of the present invention however to provide a system which is adapted for use with a combustion responsive device which is so sensitive as to be incapable, in and of itself, of providing any substantial delay between the extinguishment of the flame at the burner and the reenergization of the burner motor.

One of the main objects of the invention is to provide a fluid fuel burning system having an extremely sensitive combustion responsive device and a separate timer for timing the scavenger period on recycle.

A further object is to provide a system of the above type in which the timer acts to terminate ignition after the combustion responsive device has responded to combustion.

Another object is to provide a system of the above type in which the hot and cold combustion switches are not required to overlap in either direction and therefore may be made in the form of a snap switch.

Another object of the invention is to provide a system in which an extremely sensitive combustion responsive device and timer act conjointly to shut the system down in the event of a flame failure and the timer determines the length of the scavenger period on recycle.

These and other objects will readily become apparent to those skilled in the art as the following specification is read in the light of the accompanying drawing which involves a single figure illustrating diagrammatically a fuel burner control system embodying my invention.

Referring now specifically to the drawing, the reference numeral 10 indicates a sensitive con-

trol instrument by means of which it is desired to control the fuel burner.

In this instance the control instrument has been shown as comprising a bimetallic element 11 which is fixed at one end and which carries at its free end a pair of contact blades 12 and 13. The contact blade 12 has been made resilient so that on a decrease in temperature the bimetallic element 11 will contract and cause the blade 12 first to engage the stationary contact 14, and at a slightly lower temperature, cause the blade 13 to make contact with the stationary contact 15.

Indicated generally at 17 is an electric timer which has been illustrated as being in the form of a bimetallic blade 18 which is fixed at its lower end and which, when cold, causes its free end to engage the stationary contact 19, and when hot, warps to the left, causing its free end to engage the stationary contact 20. The free end of the bimetallic blade 18 has also been shown as operating any type of snap switch, such as the one indicated generally at 21. This snap switch has been shown for the purposes of illustration as a common type of overcenter snap switch having a movable arm 22 and an overcenter spring 23. When the timer is in cold position the snap switch is in the position shown in which the arm 22 is in engagement with the stationary contact 24. When the timer is heated and warps to the left the snap switch will be snapped to its opposite position in which the arm 22 will be in engagement with a stationary stop indicated at 25. An electrical heating element 26 is illustrated adjacent the bimetallic blade 18 for the purpose of causing it to warp from its cold to its hot position.

A combustion responsive switching mechanism has been illustrated diagrammatically as shown at 28, and comprises an arm 29 which engages a cold contact 30 in the absence of combustion and which moves into engagement with the stationary contact 31 in the presence of combustion. It will be understood that this switching mechanism is not calibrated and therefore does not respond to any set temperature. It merely responds to the presence or absence of combustion at the burner. The hot and cold switches in this switching mechanism do not overlap in either direction; that is, on heating the arm 29 first disengages the contact 30 and then engages the contact 31, while on cooling the arm first disengages the contact 31 and then engages the contact 30.

Indicated generally at 35 is any usual form of safety switch mechanism in which the contacts are normally latched closed but which may be tripped to open position by an electrically responsive timing means. In this instance, the switch is shown as comprising a pair of resilient

contact blades 36 and 37 which are biased apart but which are normally held in closed position by means of the thermal latch 38. As long as this latch is cold, the blades 36 and 37 are held in closed position, but when heated, for example by the electric heater 39, the blade 38 will warp to the right and release the switch for movement to open position. A trip free manual reset button has been shown at 40. It will be seen that when the button 40 is raised to reset the switch that the resilient blade 36 will be held out of engagement with the blade 37 during the time that the switch is being reset, so that it is impossible to manually hold the switch in closed position.

Indicated generally at 42 is an electromagnetic relay having an actuating winding 43 and a bucking winding 44. That is, when the winding 43 is energized, the relay pulls in but when the bucking winding 44 is energized while the winding 43 is energized the effect of the winding 43 is neutralized and the relay drops out. This is due to the fact that the winding 44 is wound oppositely to the winding 43 and hence when both windings are energized their magnetic effects cancel each other. The relay 42 is provided with an armature indicated by the dotted line 45, and when the relay is energized the armature pulls in to cause the contact arms 46 and 48 to engage the stationary contacts 49 and 51, respectively. When the relay is deenergized the armature drops out and the arms 46 and 48 move to open contact position either by gravity or by a spring, not shown.

The system illustrated may be operated to control the usual oil burner which comprises the usual burner motor indicated at 53 and an electric ignition device for igniting the oil shown at 54. It is obvious that this system could be used to control burners employing other types of fuel. The electrical power for operating the system is supplied by means of the line wires 56 and 57 through a step-down transformer illustrated at 58. The primary winding 59 of this transformer is connected to the line wire 56 by means of conductor 60 and to the line wire 57 by means of conductor 61. The transformer 58 is provided with a secondary winding 62.

Operation

The parts of the system have been illustrated in the drawing in the position they will occupy when the room thermostat is satisfied and has been satisfied for a sufficient length of time to permit the combustion responsive arm 29 to engage its cold contact 30 and to permit the bimetallic timer 18 to cool off sufficiently to engage its cold contact 19. Under these conditions the ignition control arm 22 will engage its contact 24, but the ignition device will not be energized at this time due to the fact that the circuit thereto is broken at the contact arm 46 and stationary contact 49. The secondary winding 62 of the transformer 58 is now disconnected from the system at the room thermostat and therefore both of the windings 43 and 44 of the relay 42 are deenergized and the relay is in its out position.

On a decrease in room temperature the contact arm 12 will first engage the stationary contact 14, but this will close no circuit to the system due to the fact that the contact arm 48 is separated from the contact 51. Nothing will happen therefore until a further decrease in room temperature causes the contact arm 13 to engage the stationary contact 15. This will es-

tablish a circuit from one side of secondary winding 62 through conductor 65, stationary contact 14, switch arms 12 and 13, contact 15, conductor 66, contact 19, timer blade 18, conductor 58, contact 38, switch arm 29, conductors 69 and 70, electric heater 39, conductors 71 and 72, safety switch blades 36 and 37, conductor 73, actuating winding 43 of the relay 42, and conductor 74 back to the other side of the secondary winding 62. As a result of this circuit the electrical heater 39 for the safety switch will be energized and the relay winding 43 will be energized which will result in the relay armature 45 pulling in and causing the switch blades 46 and 48 to engage their contacts 49 and 51, respectively. Closure of the contact blade 48 with the contact 51 will cause a holding circuit to be set up from one side of the secondary winding 62, through conductor 65, contact 14, switch blade 12, bimetallic element 11, conductor 75, contact 51, switch arm 48, conductors 76 and 78 to the electrical heater 39 and thence through conductors 71 and 72 to the safety switch and then through the actuating winding 43 and back to the other side of the secondary 62. It will be noted that this holding circuit is independent both of the bimetallic timer element 18 and the combustion responsive switch arm 29, so that any movement of these elements at this time will not drop out the relay.

Engagement of switch arm 46 with stationary contact 49 will establish three separate circuits. The first circuit extends from the line wire 56 through conductor 80, contact 49, switch arm 46, conductor 81, burner motor 53, and conductor 82 back to the other line wire 57. This circuit results in the energization of the burner motor 53 and the resultant delivery of fuel to the burner. Another circuit extends from the line wire 56 through conductor 80, contact 49, switch arm 46, conductors 83 and 84, contact arm 22, contact 24, conductor 85, ignition device 54, and conductor 86 back to the line wire 57. This circuit results in the energization of the electrical ignition device 54 for igniting the oil delivered to the burner. A third circuit is established from line wire 56, conductor 80, contact 49, contact arm 46, conductors 83 and 87, electric heating element 26 and conductor 88 back to the line wire 57. Closure of this circuit energizes the electric heater 26 which heats the bimetallic timer 18.

Inasmuch as the burner motor 53 and the electrical ignition device 54 are now both energized, combustion will normally be produced and a flame will appear at the burner. The combustion responsive device 28 will now function to move the contact arm 29 from engagement from the cold contact 30 into engagement with the hot contact 31. This establishes a shunt circuit around the heater for the safety switch and the actuating winding 43 of the relay 42 will now be energized by a circuit extending from one side of the secondary winding 62 through conductor 65, contact 14, contact blade 12, bimetallic element 11, conductor 75, contact 51, switch arm 48, conductors 76 and 69, switch arm 29, contact 31, conductors 90 and 72 through safety switch 35, conductor 73, actuating winding 43, and conductor 74 back to the other side of the secondary winding 62. Therefore the engagement of the contact arm 29 and the contact 31 effectively de-energizes the heater 39 thereby preventing the unlatching of the safety switch 35. As the bimetallic timer element 18 heats up and warps into engagement with its hot contact 20, it carries

the lower end of the overcenter spring 23 toward the left and moves it over center with respect to the contact blade 22 which causes it to disengage its contact 24 and engage the stop 25. This opens the circuit to the ignition device 54 and this device is therefore deenergized. This is the normal running condition of the system.

Upon an increase in room temperature, the bimetallic element 11 will expand and cause the switch blade to separate from the contact 15. This will not affect the system inasmuch as there is a holding circuit through the contact 14, switch blade 12 and bimetallic element 11 and down through contact 15 and switch 48. Upon a further increase in room temperature the bimetallic element 11 will expand further and cause the switch blade 12 to separate from the stationary contact 14. This will break the holding circuit to the actuating winding 43 of the relay 42 and the contact arms 46 and 48 will therefore disengage their stationary contacts 49 and 51. This will result in the deenergization of the burner motor 53 and the consequent extinguishment of the flame at the burner. As a result, the combustion responsive device 28 will cause the switch arm 29 to disengage contact 31 and reengage the cold contact 30. When a very sensitive combustion responsive device is used, this action will occur very rapidly. Therefore some other device must be used to prevent the reenergization of the burner before the proper scavenger or standby period has elapsed. This is taken care of by the bimetal timer 18. When the switch arm 46 separates from the contact 49 it also deenergizes the electric heater 26 for this bimetallic timer 18. The timer 18 will therefore cool and will, after a predetermined period of time, disengage the hot contact 20 and reengage the cold contact 19, at the same time snapping the switch blade 22 back into engagement with the stationary contact 24. The system is now in condition for a normal start with the parts in the position shown in the drawing. It will be noted, however, that the system can not restart until the bimetal timer reengages the cold contact 19, and it is therefore the timer 18 which determines the scavenger period.

In the event of a flame failure while the system is in running condition the combustion responsive device will react immediately and cause the switch arm 29 to engage the hot contact 31 and engage the cold contact 30. This will establish a circuit from one side of the secondary winding 62 through conductor 65, contact 14, switch blade 12, bimetallic element 11, conductor 75, contact 51, switch arm 48, conductors 76 and 69, switch arm 29, contact 30, conductor 68, bimetallic blade 18, contact 20, conductor 91, bucking coil 44, conductors 92 and 74 back to the other side of the secondary winding 62. It will be seen that this circuit energizes the bucking winding 44 and therefore drops out the relay armature 45, shutting the system down. When the relay armature 45 drops out it deenergizes the heater 26 for the bimetallic timer 18 and after a predetermined period of time this timer will reclose the ignition switch and contact 24 and will reengage its cold contact 19, at which time, if the room thermostat is still calling for heat, the system will attempt to restart. If the ignition of the fuel at the burner is successful at this time the system will assume its running position and will therefore return to normal. If the flame is not established at the burner, the combustion responsive device 28 will retain the

switch arm 29 in engagement with the cold contact 30 with the result that the electric heater 39 for the safety switch will remain energized, and after a predetermined period of time will release the safety switch blade 36 which will then move to open circuit position. This breaks the circuit to the actuating winding 43 for the relay 42 and the armature 45 will drop out and the system will be shut down. The system cannot now be restarted until the manual push button 40 is operated to reset the safety switch to closed position. This will not be done of course until the difficulty which prevented the establishment of combustion at the burner has been remedied.

It will therefore be seen that I have designed an intermittent ignition oil burner control system which will shut down immediately upon the failure of flame at the burner and which will recycle after a predetermined scavenger period has elapsed. It should also be noted that even though a very sensitive combustion responsive device may be used which will operate substantially immediately upon the appearance and disappearance of flame at the burner, the system cannot immediately reenergize the burner motor after it has been shut down because a timer is used to interpose a predetermined minimum time delay between successive burner energizations.

It will also be seen that I have eliminated the necessity for utilizing a combustion responsive device in which the hot and cold switches must overlap either on heating or cooling.

As many changes and modifications of this invention will undoubtedly occur to those who are skilled in the art, I wish it to be understood that I intend to be limited only by the scope of the appended claims.

40 I claim as my invention:

1. A fluid fuel burner control system comprising in combination, a burner, an electrical device for supplying fuel to the burner, a combustion responsive device having a cold switch, an electrically operated timer having a first switch which is closed when said timer is deenergized and a second switch which is closed when said timer is energized, a main switch, a first circuit including said main switch, first switch and cold switch, 45 relay means energized as a result of closure of said circuit for rendering said electrical device operative to supply fuel and for energizing said timer, said relay means closing a holding circuit for itself independent of said timer and combustion switches, and means including said second switch and said cold switch for rendering said electrical device inoperative.

2. A fluid fuel burner control system comprising in combination, an electrical device for supplying fuel to said burner, a combustion responsive device having hot and cold switches, a timer closing a first switch when deenergized and a second switch when energized, a main switch, a relay, a normally closed safety switch in control of said electrical device, electrical time delay means for opening said safety switch, an energizing circuit for said relay including said main switch, first switch, cold switch, and electrical time delay means, said relay, when energized, closing a holding circuit for itself which is independent of said first switch and cold switch, and also energizing said timer and rendering said electrical device operative to supply fuel to the burner, means for deenergizing said electrical time delay means including said hot switch, and

means for deenergizing said relay including said cold switch and second switch.

3. A fluid fuel burner control system comprising in combination, a burner, an electrical device for supplying fuel to the burner, a combustion responsive device having a cold switch, an electrically operated timer having a first switch which is closed when said timer is deenergized and a second switch which is closed when said timer is energized, a main switch, a relay having an actuating winding and a bucking winding, a first circuit including said main switch, first switch, cold switch, and actuating winding, a holding circuit closed by said relay independent of said first switch and cold switch, said relay rendering said electrical device operative to supply fuel and also energizing said timer, and a circuit for said bucking winding including said second switch and cold switch.

4. A fluid fuel burner control system comprising in combination, an electrical device for supplying fuel to said burner, a combustion responsive device having hot and cold switches, a timer closing a first switch when deenergized and a second switch when energized, a main switch, a relay, a normally closed safety switch in control of said electrical device, electrical time delay means for opening said safety switch, an actuating winding and a bucking winding for said relay, a first circuit including said main switch, first switch, cold switch, and electrical time delay means, a holding circuit closed by said relay independent of said first switch and cold switch, said relay energizing said timer and rendering said electrical device operative to supply fuel to the burner, means for deenergizing said electrical time delay means including said hot switch, and a circuit for said bucking winding including said cold switch and second switch.

5. A fluid fuel burner control system comprising in combination, a burner, an electrical device for supplying fuel to the burner, an ignition device for said fuel, an ignition switch, a combustion responsive device having a cold switch, an electrically operated timer having a first switch which is closed when said timer is deenergized and a second switch which is closed when said timer is energized, a main switch, a first circuit including said main switch, first switch and cold switch, relay means energized as a result of closure of said circuit for rendering said electrical device operative to supply fuel, for rendering said ignition device operative to ignite said fuel, and for energizing said timer, said timer subsequently opening said ignition switch to terminate ignition, said relay means closing a holding circuit for itself independent of said timer and combustion switches, and means including said second switch and said cold switch for rendering said electrical device inoperative.

6. A fluid fuel burner control system comprising in combination, an electrical device for supplying fuel to said burner, an ignition device for igniting said fuel, an ignition switch, a combustion responsive device having hot and cold switches, a timer closing a first switch when deenergized and a second switch when energized, a main switch, a relay, a normally closed safety switch in control of said electrical device, electrical time delay means for opening said safety switch, an energizing circuit for said relay including said main switch, first switch, cold switch, and electrical time delay means, said relay, when energized, closing a holding circuit for itself which is independent of said first switch and

cold switch, and also energizing said timer, rendering said electrical device operative to supply fuel to the burner, and rendering said ignition device operative to ignite said fuel, means for deenergizing said electrical time delay means including said hot switch, said timer operating as a result of its energization to open said ignition switch, and means for deenergizing said relay including said cold switch and second switch.

10. 7. A fluid fuel burner control system comprising in combination, a burner, an electrical device for supplying fuel to said burner, a combustion responsive device having a hot switch and a cold switch, a timer switch, a timer for closing said timer switch when deenergized and opening said timer switch when energized, a main switch, a relay, a normally closed safety switch in control of said electrical device, electrical time delay means for opening said safety switch, an energizing circuit for said relay controlled by said main switch, timer switch, and electrical time delay means, said relay, when energized, closing a holding circuit for itself which is independent of said timer switch, and also energizing said timer and rendering said electrical device operative to supply fuel to the burner, means including said hot switch for deenergizing said electrical time delay means, and means including said cold switch and said timing device for deenergizing said relay for a timed period upon combustion failure.

15. 8. A fluid fuel burner control system comprising in combination, a burner, an electrical device for supplying fuel to said burner, an ignition device for said fuel, an ignition switch, a combustion responsive device having a hot switch and a cold switch, a timer switch, a timer for closing said timer switch when deenergized and opening said timer switch when energized, a main switch, a relay, a normally closed safety switch in control of said electrical device, electrical time delay means for opening said safety switch, an energizing circuit for said relay controlled by said main switch, timer switch, and electrical time delay means, said relay, when energized, closing a holding circuit for itself which is independent of said timer switch, and also energizing said timer and rendering said electrical device operative to supply fuel to the burner, an energizing circuit for said ignition device closed upon energization of said relay, said timer opening said ignition circuit after a predetermined period of time, means including said hot switch for deenergizing said electrical time delay means, and means including said cold switch and said timing device for deenergizing said relay for a timed period, upon combustion failure.

20. 9. In burner control mechanism for an electrical device for controlling the supply of fuel to a burner, a combustion responsive device having a cold switch, an electrically operated timer having a first switch which is closed when said timer is deenergized and a second switch which is closed when said timer is energized, means for establishing a first circuit including said first switch, said cold switch, and a main switch, relay means energized as a result of closure of said circuit and adapted to render said electrical device operative to supply fuel and for energizing said timer, said relay means being adapted to close a holding circuit for itself independent of said timer and combustion switches, and means including said second switch and said cold switch for causing deenergization of said relay.
